APPARATUS FOR BLENDING FIBER

Leslie A. Runton, Dracut, Mass., assignor to J. P. Stevens & Co. Inc., New York, N. Y., a corporation of Delaware

Application May 25, 1949, Serial No. 95,357

14 Claims. (Cl. 19—146)

1

This invention relates to an apparatus for the blending of fibre.

Fibre has long been blended by hand by scattering the fibre in sections over the floor and repeating the process until a layer has been built up and this general procedure has also been carried out by feeding the fibre to a conveyor consisting of a long bank of rolls. These rolls are driven in one direction to advance the fibre. Then alternate rolls are stopped and driven in the opposite direction and the fibre is fed downward between pairs of rolls thus rotating in opposite directions and discharged in sections on the floor beneath or upon a traveling belt. This operation is repeated until a layer of fibre of desired thickness is built up.

The object of the present invention is to secure a proper and efficient blending of the fibre while enabling the operation to proceed rapidly and with the maximum economy. The broad principle of the invention, which may be carried out with and embodied in different types of apparatus, resides in causing the fibre in sheet form constantly to advance, to be divided into sections while advancing, and then these sections to be discharged downward while still advancing. In other words, the principle involved is the continual movement of the fibre from the time the operation is begun in an advancing direction while it is being divided and until it reaches the floor or support upon which the blending takes place. Thus there is no reversal of the movement of the fibre and no reversal of movement of the conveyor during the entire operation. It is this principle which enables the operation to be carried out at high speed and the fibre to be blended efficiently and economically.

The apparatus of the present invention is subsidiary to this broad principle disclosed and made the subject of claims in an application filed concurrently herewith, Serial No. 95,356, filed May 25, 1949. In the embodiment of this broad principle the apparatus of the present invention comprises essentially a conveyor comprising a series of parallel rolls to which the fibre is fed and in which all the rolls are rotated only in one direction, with the rolls positioned in a substantially horizontal plane and spaced to support and advance in sheet form the fibre fed thereto, together with means actuated, each time the sheet of fibre advanced by the rolls reaches a predetermined point, to effect a relative bodily movement of the adjacent rolls of the series which causes the sheet of advancing fibre to be separated into sections and the sections while still advancing to be discharged downward.

2

Various forms of apparatus embodying this principle, each of which also embodies novel and subsidiary features of the invention, are disclosed herein.

5 The nature and objects of the invention will more fully appear from the accompanying description and drawings and will be pointed out in the claims.

The illustrated embodiments of the invention are in more or less diagrammatic form and with only those features shown in detail which are necessary to an understanding of the different forms of apparatus.

In the drawings:

15 Fig. 1 is a top plan view of the main elements of one form of apparatus together with a section for expanding into sheet form and feeding fibre in sheet form thereto;

20 Fig. 2 is a side elevation of the construction shown in Fig. 1 with the rolls of the conveyor indicated in the position for downward discharge of the sheet of fibre separated into sections, the relative movement of adjacent rolls of the series in this form being a relative bodily movement. [It is to be understood that only a small portion of the series of rolls are shown in this and the preceding figure. This figure also indicates a belt upon which the sections of fibre are discharged, but it will be understood that such a belt when used would be placed much further below the series of rolls.]

25 Fig. 3 is a view mainly in longitudinal vertical cross section and partially broken away of one of the rolls of the series;

30 Fig. 4 is a side elevation of a group of the rolls indicated in the preceding figures, and illustrating the mechanism for effecting relative bodily movement of adjacent rolls of the series, with the rolls shown in position for supporting and advancing the fibre in sheet form;

35 Fig. 5 is a view similar to Fig. 4, showing the rolls in the position occupied for separating the sheet of fibre into sections and discharging the sections while advancing downward;

40 Fig. 6 is a side elevation of the main features of a second form of apparatus, with the central portion broken away and of a type in which alternate rolls are given a bodily vertical movement with respect to the other rolls to effect the separation of the sheet of fibre into sections and the discharge of the sections while advancing downward;

45 Fig. 7 is a view similar to Fig. 6 showing the alternate rolls vertically displaced with the sheet of fibre separated into sections and advancing downward;

Figs. 8, 9, and 10 illustrate a third form of apparatus in which the series of parallel rolls have their ends journaled and mounted to slide in a substantially horizontal plane, and in which a relative bodily movement of the adjacent rolls is secured by separating the rolls in the same plane, Fig. 8 being a top plan view of a portion of one side partially in horizontal cross section, Fig. 9 being a side elevation with the rolls in position for supporting and advancing the sheet of fibre, and Fig. 10 being a side elevation with the rolls spaced to separate the sheet of fibre into sections and discharge the sections while advancing downward.

The fibre to be blended is fed in substantial sheet form to the series of rolls of the conveyor and any suitable means for thus forming the fibre into substantially sheet form and feeding it may be employed. In Figs. 1 and 2 the left hand portion illustrates one form of mechanism for this purpose. In this form a series of arcuate bars, herein shown as eleven in number, with the first of these bars beginning at the left hand bar 1 and ending at the right hand bar 2 gradually increasing both in length and in radius of curvature until the right hand bar 2 extends in approximate parallelism to the rolls of the conveyor, are mounted on curved supports 3 of the frame of the machine. On each bar is rotarily mounted by suitable bearings, not shown, a shell 4 of circular cross section of flexible material, such as rubber, and these shells are simultaneously rotated by suitable mechanism with the result that fibre deposited at the left hand end of the series is gradually advanced and spread out into substantially sheet form and delivered in that form to the rolls of the conveyor. But it is to be understood that the fibre may be delivered in sheet form by any other means such as from an endless apron or belt as hereinafter illustrated.

In the form of the invention illustrated in Figs. 1 to 5 inclusive there are two series of rolls each of which is continuously rotated by suitable means and each of which for that purpose may have the construction illustrated more in detail in Fig. 3. Alternate rolls 5, as shown in Figs. 4 and 5, are mounted at their ends on brackets 6 secured to supports 7 at opposite sides of the frame which supports may be a continuation of the curved supports 3. Alternating with the rolls 5 are the rolls 8 and these rolls at their ends are shown mounted at each side in the upper arms of bell crank levers 9 fulcrumed at 10 coaxially with the rolls 5 on the bracket 6. Suitable means are provided for simultaneously operating the bell crank levers so as to swing the rolls 8 vertically between the positions shown in Figs. 4 and 5.

The construction of each of the rolls 5 and 8 is preferably the same and one of the rolls 5 is illustrated in Fig. 3 together with an electric motor for rotating the roll. In this construction the electric motor 11 is secured to a disk-shaped base 12 having a central projecting shaft 13 rigidly secured, as by the set screw 14, in one of the brackets 6. A shaft 15 in axial alignment with the shaft 13 is journaled in the upper end of the opposite bracket 6. The surface of the roll is shown as a cylindrical metal shell 16 and is preferably provided with a plurality of longitudinally projecting flanges 17. This shell is mounted on and secured to a plurality of disks 18 pinned to the shaft 15 and the shell at the end extends over and close to the disk 12. The motor 11 is held in axial alignment with the shaft 15 already described the principal difference being

15 by means of an arm 19 secured to the motor and projecting therefrom with one raceway 20 of a ball bearing secured to the arm 19 and co-operating with the other member of the ball bearing secured to the shaft 15. The shaft of the motor has secured thereto a pinion 21 meshing with an internal gear 22 secured to the shell 16 of the roll. The motor is energized by current connected at 23. It will thus be seen that the motor when driven acts to rotate the roll about its central axis.

The rolls extend in a long series to any required extent and a series of about fifty rolls has been found desirable. Since the action is the same throughout only the last three pairs of rolls are illustrated in Figs. 4 and 5. These rolls, as by means of electric motors, are all continuously rotated in one direction and in the position shown in Fig. 4 are positioned in a substantially horizontal plane and spaced so as to support and advance in sheet form the fibre fed thereto. Periodically the series of rolls 8, while all the rolls are still rotating, are moved bodily vertically upward by the simultaneous operation of the bell crank levers 9 to a position such as indicated in Fig. 5 with the result that the sheet of fibre is separated into sections and while still advancing is discharged downward, usually with the sections feeding down off the rolls 8 on to the rolls 5, and then down.

This periodic movement of the rolls to separate the sheet of fibre into sections may be determined as desired. Preferably it is determined by the edge of the advancing sheet of fibre reaching the end of the series and engaging an actuating means, such as an electric eye mechanism, illustrated diagrammatically at 24.

So also the mechanism for operating the bell crank levers 9 may take any suitable form. In the construction illustrated in each case the lower arm 25 of the bell crank lever is pivoted to a piston rod 26 of a piston mounted in a cylinder 27 pivoted at 28 to the side frame 7. The opposite ends of the cylinder are connected to a valve 29 connected in turn by a pipe 30 to a suitable source of compressed air. The valve 29 is connected by an arm 31 to the core of a solenoid 32. The indication given by the electric eye 24, or by whatever means may be employed, is caused by suitable electric connections to actuate the solenoid 32 to actuate the valve 29 and admit air to the cylinder to move the piston from the position shown in Fig. 4 to that shown in Fig. 5, and then to admit the air to the other end of the cylinder and reverse the operation. This action takes place practically momentarily because the fibres are advancing rapidly and the separated sections of fibre are quickly discharged downward.

60 Thus it will be seen that the sheet of fibre fed to the conveyor is constantly advancing until it reaches the floor or support beneath the apparatus to form the blend. This advancing movement therefore occurs while the sheet of fibre 65 is being separated into sections and in this form of the invention the separation into sections is effected by a relative movement, in this case a relative bodily movement, and more particularly a relative bodily vertical movement, of the adjacent rolls of the series which takes place while the fibre is still advancing.

A second form of embodiment of the invention is illustrated in Figs. 6 and 7. This construction is generally similar to that of the first form 75 already described the principal difference being

that in effecting the separation of the sheet of fibre into sections one series consisting of alternate rolls is moved vertically in a straight line with the moved rolls carried by a support moving as a unit.

In this construction a framework shown as having side bars 60 with vertical struts 61 is secured to the ceiling or other support with the frame extending horizontally. One series of rolls 62 is supported in brackets 63 depending from the bars 60 of the frame. The other series of alternate rolls 64 are supported in brackets 65 mounted on a horizontal frame having side members 66. Here again only a portion of the long series of rolls is illustrated. Each of the rolls is illustrated as of the same construction as shown in Fig. 3 and previously described, and the motors of all the rolls are actuated by the current supplied thereto to cause all the rolls to rotate in the same direction.

The lower frame carrying the rolls 64 is mounted on vertical piston rods 67, the pistons of which are controlled by cylinders 68 supported on a suitable rigid base 69. As described in connection with the previous form compressed air is supplied through the pipes 70 to a valve 71 having connections 72 and 73 to the opposite ends of the cylinder and this valve is provided with an arm 74 operated by a solenoid 75.

With all the rolls standing in a substantially horizontal plane, as indicated in Fig. 6, the fibre is fed in any suitable manner as from the endless conveyor belt 76 to the rolls so as to lie in substantial sheet form and thereupon is steadily advanced by the rotation of the rolls. When the leading portion of the sheet of fibre reaches a predetermined point the valves 71 are actuated to cause the frame carrying the rolls 64 to move vertically downward momentarily to a position such as shown in Fig. 7 and then to return to the position shown in Fig. 6. The operation of the valves 71 to effect this movement may be determined by any suitable means but again is assumed to be determined by the advancing edge of the sheet of fibre actuating an electric eye mechanism 77 which in turn controls the action of the solenoids 75.

Thus it will be seen that the sheet of fibre fed to the conveyor is constantly advancing until it reaches the floor or support beneath the apparatus to form the blend. This advancing movement therefore occurs while the sheet of fibre is being separated into sections and in this form of the invention the separation into sections is effected by a relative movement, in this case a relative bodily movement, and more particularly a relative bodily vertical, straight line movement, of the adjacent rolls of the series which takes place while the fibre is still advancing.

A third form of apparatus embodying the invention is illustrated in Figs. 8, 9, and 10. In this form the rolls of the conveyor remain in the substantially horizontal plane, both in the position in which the sheet of fibre is advanced by the rolls in sheet form and in the position in which the fibre is separated into sections and the sections discharged downwardly while still advancing. In this case the rolls are brought to the latter position to effect the separation of the sheet of fibre into sections by a relative bodily movement acting to space adjacent rolls further apart than in the position while advancing the fibre in sheet form and preferably this movement to effect the spacing apart of adjacent rolls is

effected in regular sequence beginning at both ends of the series.

In the construction illustrated a suitable framework having track bars 80 at each side is suitably supported as by vertical standards 81 well above the floor. This framework carries at each side a plurality of similar trolleys each shown as consisting of a vertical bar 82 having a head 83 in which is journaled a pair of trolley wheels 84 riding in the track 80. Each bar 82 at its lower end has rigidly secured thereto and extending in each direction horizontally therefrom a link 85 with the ends of the links slotted and the ends of adjacent links overlapped laterally as will be seen from the plan view in Fig. 8.

The rolls 86 are indicated of the same construction and operation as illustrated in Fig. 3 and previously described. The shafts 87, corresponding to the shafts 13 and 15 shown in Fig. 3, are supported in the slots of the links with a trolley located between each adjacent pair of links and with the shafts 87 extending through both links where the links overlap. Since the shaft 87 at the end of the roll carrying the motor does not rotate it is necessary to provide some means for preventing rotation and for that purpose each roll is shown as provided with a hub 88 secured to the shaft 87 at the said end and having a flat surface sliding on a horizontally arranged guide bar 89 forming a part of the framework.

When the end link elements of the series are pushed the rolls are brought to a position such as illustrated in Fig. 9 where they are spaced to support and advance in sheet form the fibre fed thereto. When the end link elements are pulled the rolls beginning at the end are spaced apart in regular sequence and act to separate the sheet of fibre into sections.

Since the series of rolls is, as previously pointed out, a very long series, it is desirable in this type of apparatus to divide the rolls into two series, as shown in Figs. 9 and 10, it being understood that the four rolls shown in each series are but illustrative in each case of a far greater number. With the rolls thus divided into two series the end link elements at both ends of the entire series are simultaneously pushed to bring the rolls into the position illustrated in Fig. 9 and pulled to bring the rolls into the position illustrated in Fig. 10.

Any suitable means may be employed for periodically thus moving the rolls. As illustrated the end link elements are shown as connected to rack bars 90 operated by gears 91 driven by electric motors 92, one of which is shown at the left of Fig. 9.

With the rolls arranged in the first position, as shown in Fig. 9, the fibre is fed thereto by any suitable mechanism such as the endless apron or conveyor 93. The rolls driven by their motors all rotate in the same direction, as previously described, and act continuously to advance the fibre in sheet form. When the leading edge of the fibre, as before, has reached a predetermined point, suitable mechanism acts to start the motors 92 and cause the adjacent rolls in regular sequence to be spaced further apart, or to a position such as shown in Fig. 10; and thereupon the rolls act to separate the sheet of fibre into sections and discharge these sections while still advancing downward. Then the operation of the motor is reversed and the rolls returned to the position illustrated in Fig. 9. Thus it will be seen that the sheet of fibre fed

to the conveyor is constantly advancing until it reaches the floor or support beneath the apparatus to form the blend. This advancing movement therefore occurs while the sheet of fibre is being separated into sections and in this form of the invention the separation into sections is effected by a relative movement, in this case a relative bodily movement, and in this case with the bodily movement of the rolls taking place while they remain in the horizontal plane and are separated horizontally in regular sequence, all of which takes place while the fibre is still advancing.

Having thus described the invention, what is claimed as new, and desired to be secured by Letters Patent, is:

1. An apparatus for blending fibre comprising a series of parallel rolls, means for rotating all the rolls only in one direction, means for mounting adjacent rolls for relative bodily movement while remaining parallel between a position in which all the rolls are in a substantially horizontal plane and spaced to support and advance in sheet form the fibre fed thereto and a second position to which the adjacent rolls have been displaced by the said relative bodily movement, said movement acting to separate the sheet of fibre into sections thereby to discharge the sections, while advancing, downward, and means for periodically effecting the said relative movement of the rolls between the said two positions.

2. An apparatus for blending fibre as defined in claim 1, together with means actuated by the sheet of fibre advanced by the rolls when in the first position acting to initiate the operation of the said means for periodically effecting the said relative movement.

3. An apparatus for blending fibre comprising a series of parallel rolls, means for rotating all the rolls only in one direction, means for mounting adjacent rolls for relative bodily movement while remaining parallel between a position in which all the rolls are in a substantially horizontal plane and spaced to support and advance in sheet form the fibre fed thereto and a second position to which the adjacent rolls have been displaced by the said relative bodily movement, said movement acting to separate the sheet of fibre into sections thereby to discharge the sections, while advancing, downward, and means actuated, each time the sheet of fibre advanced by the rolls when in the first position reaches a predetermined point, to move the rolls to the second position and, after the discharge of the fibre, move the rolls to the first position.

4. An apparatus for blending fibre as defined in claim 1, in which the means for periodically effecting the said relative movement of the rolls acts to cause the rolls to move in the said horizontal plane.

5. An apparatus for blending fibre as defined in claim 1, in which the means for periodically effecting the said relative movement of the rolls acts to cause the rolls to move in regular sequence in the said horizontal plane.

6. An apparatus for blending fibre as defined in claim 1, in which the means for periodically effecting the said relative movement of the rolls acts to cause the rolls to move beginning at both ends of the series in regular sequence in the said horizontal plane.

7. An apparatus for blending fibre comprising two series of parallel rolls with the rolls of one series alternating with the rolls of the other series, means for rotating all the rolls only in one direction, means for feeding fibre on to the

rolls, means for mounting the said two series of rolls for relative bodily movement while remaining parallel between a position in which all the rolls are in a substantially horizontal plane and spaced to support and advance in sheet form the fibre fed thereto, and a second position in which the rolls of one series are displaced from the rolls of the other series and the two series of rolls act to separate the sheet of fibre into sections and discharge the sections, while advancing, downward, and means for periodically effecting the relative movement of the two series of rolls between the said two positions.

8. An apparatus for blending fibre as defined in claim 7, in which the means for periodically effecting relative movement of the two series of rolls acts to cause the rolls of a series moved to move simultaneously.

9. An apparatus for blending fibre comprising two series of parallel rolls with the rolls of one series alternating with the rolls of the other series, means for rotating all the rolls only in one direction, means for feeding fibre on to the rolls, means for mounting the said two series of rolls for relative bodily movement while remaining parallel between a position in which all the rolls are in a substantially horizontal plane and spaced to support and advance in sheet form the fibre fed thereto, and a second position in which the rolls of one series are displaced vertically from the said plane and the two series of rolls act to separate the sheet of fibre into sections and discharge the sections, while advancing, downward, and means for periodically effecting the relative movement of the two series of rolls between the said two positions.

10. An apparatus for blending fibre comprising two series of parallel rolls with the rolls of one series alternating with the rolls of the other series, means for rotating all the rolls only in one direction, a frame, supports on the frame mounting one series of rolls in fixed position in a substantially horizontal plane, movable supports for the other series of rolls movably mounted on the frame and acting in one position to maintain the said series of rolls in the same plane as the fixed series and acting when moved to a second position to raise the said series above the fixed series of rolls, the rolls of both series when in the said horizontal plane being spaced to support and advance fibre in sheet form fed thereto, and when in the second position acting to effect the separation of the sheet of fibre into sections and discharge the sections, while advancing, downward, and means for periodically moving the movable supports from the first to the second and back to the first position.

11. An apparatus for blending fibre as defined in claim 10 in which the movable supports are bell crank levers fulcrumed on the frame with the rolls mounted on the upper arms.

12. An apparatus for blending fibre as defined in claim 10 in which the movable supports are bell crank levers fulcrumed on the frame with the rolls mounted on the upper arms, and in which the means for periodically moving the supports comprises cylinder and piston elements connecting the lower arms of the bell crank levers to the frame and valve controlled means for effecting the relative movement of the cylinders and pistons.

13. An apparatus for blending fibre comprising a series of parallel rolls having their ends journaled and mounted to slide in a substantially

horizontal plane, means for rotating all the rolls in one direction, link elements connecting adjacent rolls at each side of the series acting to hold the rolls either in a position spaced to support and advance in sheet form the fibre fed thereto or in a second position in which adjacent rolls are further spaced and act to separate the sheet of fibre into sections and discharge the sections, while advancing, downward, and means acting periodically to pull the end link elements of the series to move the rolls from the first to the second position and after the discharge of the sections of fibre acting to push the said link elements to move the rolls from the second to the first position.

14. An apparatus for blending fibre comprising a series of parallel rolls having their ends journaled and mounted to slide in a substantially horizontal plane, means for rotating all the rolls in one direction, link elements connecting adjacent rolls at each side of the series acting to hold the rolls either in a position spaced to support and advance in sheet form the fibre

fed thereto or in a second position in which adjacent rolls are further spaced and act to separate the sheet of fibre into sections and discharge the sections, while advancing, downward, and means acting periodically to pull the end link elements at both ends of the series in opposite directions to move the rolls from the first to the second position and, after the discharge of the fibre, acting to push the said link elements to move the rolls from the second to the first position.
